UNITED STATES PATENT OFFICE.

WILLIAM J. RUFF, OF QUINCY, ILLINOIS, ASSIGNOR, BY MESNE ASSIGNMENTS, TO CHARLES J. TAGLIABUE, OF BROOKLYN, NEW YORK.

THERMOSTATIC TEMPERATURE-REGULATOR.

No. 920,883.

Specification of Letters Patent.

Patented May 4, 1909.

Application filed July 26, 1907. Serial No. 385,657.

To all whom it may concern:

Be it known that I, WILLIAM J. RUFF, a citizen of the United States, and a resident of Quincy, in the county of Adams, State of Illinois, have invented certain new and useful Improvements in Thermostatic Temperature-Regulators, of which the following is a specification.

My invention relates to temperature regulators or thermostats and has for its object to provide a simple and reliable apparatus of this character which can be taken apart readily, which will be very sensitive and in which the controlling part of the apparatus can be installed at a distance from the part exposed to heat so that the controller will not be injuriously affected by vapors, etc.

The apparatus comprises two principal parts, to wit, a thermostat, that is a device exposed to heat, and a controller connected with the thermostat and having means, actuated by the change of pressure due to increase or decrease of temperature, for operating some mechanism controlling the temperature. For instance, if it is desired to regulate the temperature of an apparatus heated by steam, the controller would be capable of throttling or even entirely shutting off the flow of steam.

A typical example of my invention is shown in the accompanying drawings, in which—

Figure 1 is a sectional elevation of the controller part of the apparatus; Fig. 2 is a plan of the controller; Fig. 3 is a longitudinal section of the thermostat; and Fig. 4 is a diagrammatic view showing the invention applied to a heater.

A may represent a tank heated by steam entering at A' and leaving at A². B is the thermostat, C the controller located at a distance therefrom, and D the (metal) tube connecting them. Preferably a flexible capillary tube of copper is employed. The thermostat comprises a bulb E, partially or entirely filled with a fluid (liquid or gas) volatile liquids being suitable in many cases. This bulb is permanently connected with the extension E' and with the tube D, the joints between these parts being perfectly tight. The extension E' has a tapering portion adapted to engage a like seat of a socket F threaded externally and internally. The external thread is for connecting the socket with the tank A or other apparatus.

The closed inner end of the socket, which projects into the apparatus, is held in close contact with the bulb E by means of a union or screw plug G which screws into the socket F and also presses the tapering or conical surfaces of the extension E' and socket F closely together, these surfaces being carefully finished to obtain a tight fit. It will be understood that by simply unscrewing the plug G, the bulb E and extension E' may be removed from the socket F, the latter remaining connected with the tank, so that the heating operation may continue in the tank if a new bulb and connections are to be inserted. Quick repairs may thus be made to the thermostat.

The other end of the tube D is connected with what I term a capsular spring H, that is a chamber the walls of which are made of two wavy or elastic metal plates having a tendency to contract under the influence of atmospheric pressure. The expansion of the fluid contained in the bulb E however tends to enlarge the chamber H. One of the end plates of said chamber is permanently connected with the tube D and with a plug or nipple J suitably supported in the controller casing K. These parts, that is the capsular spring H with its support J, the tube D, and the bulb E with extension E' and screw plug G, are quickly removable, and by having a set of these parts in reserve, the apparatus can be restored to operativeness in a very short time in case of breakage. The tube D may be covered with a protector, and as a flexible armored tube.

The vertically movable central portion of the upper wall of the capsular spring H is adapted to engage, when it has risen a certain distance, the lower end of a screw L adjustable in a lever M. For this purpose the screw may have an angular head L' adapted to be engaged and turned by a suitable key. The screw L has secured to it a pointer L² adapted to indicate on a scale M' which may be graduated according to degrees of temperature. The scale or dial M' is rigidly fastened to the lever M which is fulcrumed at M² on the controller casing K and carries a weight M³ at its free end. Unless the lever is raised by the expansion of the capsular spring H, the weight M³ is supported by a stem N resting on a ball valve O supported on the valve seat P' of a stationary valve cas-

ing P. The ball and stem are separate parts engaging each other loosely, so as to avoid side strains. The stem N is guided in a plug Q screwing into the upper end of the valve 5 casing, and there is sufficient looseness around the stem to afford a vent and allow of the escape of fluid from the chamber P² above the ball valve O. This chamber is in communication with the passage P³ leading to a 10 controlled device, say a diaphragm chamber operatively connected with a throttle valve governing the flow of steam to the tank A. Such devices being well-known in the art, I have not shown them in detail in the drawings. The top wall of the chamber P² has a 15 valve seat P⁴ at the opening in which the stem N works, so that when the valve O is raised against said seat, the chamber P² no longer communicates with the open air. 20 The lower valve seat P' has a supply channel P⁵ connected with a compressed air pipe or other source of fluid under pressure.

Under certain conditions, the screw L will 25 be out of engagement with the capsular spring H and the weighted lever M will by pressing on the stem N hold the valve O down on its lower seat P', preventing the inflow of fluid under pressure through the channel P⁵, but allowing any fluid which has 30 previously reached the passage P³ to escape therefrom to the open air through the chamber P² and the central bore of the plug Q. The throttle valve controlled by the diaphragm or other device to which the passage 35 P³ leads, will therefore be fully open. If the temperature in the tank A should rise too high, the expansion of the volatile or other fluid in the bulb E, being propagated through the tube D, will raise the upper wall of the 40 capsular spring until it engages the end of the screw L, and will then lift said screw with the lever M. This relieves the pressure keeping the valve O on its lower seat, and pressure from the channel P⁵ will lift the valve and 45 pass through the chamber P² and passage P³ to the diaphragm or other device controlling the throttle valve. The latter will be closed more or less according to the lift of the valve O, and the amount of steam flowing to the 50 tank A being reduced proportionately, the temperature will fall to the desired degree. It will be understood that only when the valve O is lifted fully against the upper seat P⁴, will the full pressure from the channel P⁵ 55 reach the passage P³, but in case of a partial lift some of the fluid under pressure will exhaust through the central channel of the plug Q. The normal position of the valve O (that is, when the temperature is just right) 60 will be away from both seats P', P⁴, so that the throttle valve will be partly open. A very slight increase of temperature (as little as 1° F.) will bring the valve O nearer to or even against the upper seat P⁴, causing a 65 further closing of the throttle valve, while a

similar fall of temperature will bring the valve O nearer to or down upon its lower seat P', causing the throttle valve to open more fully. In practice, the valve O will generally flutter up and down in accordance with slight variations in temperature.

The apparatus having once been set for a certain temperature, will be very sensitive and reliable to preserve it. If it is desired to set it for a higher temperature, the screw 75 L is adjusted upward, and for maintaining a lower temperature, the screw is adjusted downward, the pointer L² indicating the control temperature on the dial or scale M¹.

Various modifications may be made without departing from the nature of my invention as defined in the claims.

I claim:

1. A temperature controller, comprising a socket having a closed inner wall and adapted to be secured to the apparatus whose temperature is to be regulated, a bulb secured within said socket, a tube one end of which communicates with said bulb, a capsular spring communicating with the other end of said tube, a support for said spring, and mechanism governed by the movement of the spring, the said capsular spring, the tube, and the bulb being permanently connected and removable and exchangeable together.

2. A socket adapted to receive the bulb of a thermostat, said socket being closed at one end, open at the other, and provided with an internal seat flaring toward said open end and adapted to engage a tapered extension 100 of the bulb, and a perforated screw plug fitted into the open end of the socket and adapted to press said extension of the bulb toward said seat.

3. A thermostat comprising a socket having a closed end and provided with an inclined seat, a bulb located within the socket and provided with a tubular extension having a taper to fit said seat, a perforated plug surrounding a portion of said extension and 105 having a screw connection with the socket, and arranged to press the tapered portion of the extension against said inclined seat, a tube communicating with said bulb and extending through said extension and mechanism connected with said tube and operated by the expansion and contraction of the fluid contained in the bulb and tube.

4. A controller comprising a valve casing having a channel for the admission of fluid under pressure, a chamber to which said channel leads, a vent from said chamber, valve seats located at the inner ends of the said channel and vent respectively, a passage connected with said chamber and arranged 120 to communicate with the controlled mechanism, a ball valve contained in said chamber and arranged to engage either seat, a stem passing through the vent with a clearance and arranged to engage the valve, and 125 130

thermostatically controlled means for pressing said stem and valve toward the seat at the inner end of the admission channel.

5. The combination of a bulb, a capsular spring, a tube connecting the bulb with the spring, a lever mounted adjacent to said spring, a projection carried by said lever and located in registry with the central portion of the spring, means for adjusting the lever 10 for various predetermined temperatures, means connected with the lever, for pressing the projection toward the capsular spring, a stem engaged by said lever at one end, a ball engaged by the other end of the stem, a valve 15 chamber containing said ball and provided with a vent through which the stem passes with a clearance, said chamber being also provided with an inlet on the side of the ball opposite to the stem, to admit fluid under 20 pressure, and with a passage arranged to communicate with the controlled mechanism.

6. The combination of a bulb, a capsular spring, a tube connecting the bulb with the

spring, a lever mounted adjacent to said 2 spring, a screw carried by said lever and arranged to engage the central portion of the spring, a dial and pointer connected one with the lever and the other with the screw, to indicate their relative positions, means, 30 connected with the lever, for pressing the screw toward the capsular spring, a stem engaged by said lever at one end, a ball engaged by the other end of the stem, a valve 35 chamber containing said ball and provided with a vent through which the stem passes with a clearance, said chamber being also provided with an inlet on the side of the ball opposite to the stem, to admit fluid under 40 pressure, and with a passage arranged to communicate with the controlled mechanism.

In testimony whereof, I have hereunto set my hand this 15th day of April, 1907.

WILLIAM J. RUFF.
